TIMING MEANS EMPLOYING CYCLE COUNTING RELAYS

Orval L. Utt, Morgantown, W. Va., assignor to Westinghouse Air Brake Company, Wilmerding, Pa., a corporation of Pennsylvania

Application April 21, 1954, Serial No. 424,624

10 Claims. (Cl. 317—142)

My invention relates to timing means employing cycle counting relays, and particularly to a means for causing immediate operation of counting relays used for counting the cycles of a reference or source potential while a vehicle is traversing a fixed distance.

In previous timing devices the counting relays may not become immediately responsive upon vehicle entrance into a timing stretch if the circuit is completed during a decreasing portion of any half cycle of reference voltage. Thus the relays would only respond when the wave form of the frequency passes through zero and begins to increase (in either the positive or the negative direction).

Since the selected traversing distance of the vehicle along a timing span for many applications is necessarily of extremely short length, the loss of a quarter of a cycle of the reference frequency by the counting relays used for timing purposes may cause considerable error in the timing results.

Further error is introduced in previous devices by the failure to provide a reset means for returning the counting relays to their initial position following a prior operation due to a prior vehicle passage.

In practicing my invention I provide a counting relay reset circuit for returning the counting relay contacts to their normal or initial position during the first half cycle of the reference potential following a previous timing operation. I also provide circuit means for varying the phase relationship of the counting relay potential with respect to the reference potential so that the relay voltage will remain at zero at all times prior to vehicle entry into a timing stretch. It thus can be seen that by ceasing the phase shifting of the counting relay potential upon entry of a vehicle into a timing stretch, the relay potential will be a rising instantaneous potential from zero without any delay.

It is therefore an object of my invention to provide a novel and improved means for returning the contacts of the cycle counting relays to their initial position following a prior operation.

Another object of my invention is to provide a novel means for eliminating the time delay of the cycle counting relays upon circuit completion.

Other objects, purposes and characteristic features of my present invention will be in part obvious from the accompanying drawing which is a diagrammatic view showing one form of timing means embodying my invention, and in which corresponding parts are generally identified by corresponding reference characters.

Referring to the drawing, the timing means as herein shown comprises four major components. The first component is a reference voltage and supply means, the second is a plurality of counting relays, the third a phase-shifting circuit and the fourth a counting relay reset circuit.

The reference voltage or potential is designated by the reference character E1, and is an alternating potential such as 60 or 100 cycles. This potential is applied to the

2

primary winding P1 of a transformer T1 having secondary windings S1 and S2. Connected in series with a resistor R6 across the secondary winding S1 are the windings W1 and W2 of a saturable reactor A. Connected between a center tap 31 on the secondary winding S1 of transformer T1 and a point 32 between the resistor R6 and the saturable reactor winding W1 is a primary winding P2 of a transformer T2. A secondary winding S3 of the transformer T2 is connected with the windings of a pair of relays PX and NX in such a manner that the PX relay responds only to positive pulses of an alternating current cycle, while the NX relay responds only to the negative pulses of a cycle upon closure of a manually or automatically controlled contact C1.

The relays PX and NX comprise the counting relays, and have associated therewith two oppositely poled rectifiers 16 and 17.

The relays PX and NX are of the quick acting two-winding polar magnetic stick type, and as shown in the drawing are in their normal or initial positions. The winding 18 of the relay PX is connected with the secondary winding S3 over a normal contact 14 of the relay NX, rectifier 17, and normally open contact C1. The other winding 19 is connected across the secondary winding S3 over the reverse contact 15 of the relay NX, rectifier 17 and the contact C1. In a similar manner, the winding 20 of the relay NX is connected to the secondary S3 over the reverse contact 13 of the relay PX, rectifier 16, and contact C1, while the other winding 21 is connected across the winding S3 over a normal contact 12 of the relay PX, rectifier 16 and contact C1. The rectifiers 34 and 35 are used to improve the operation of the relays PX and NX.

The rectifiers 16 and 17 are so poled that the relay PX will respond only to the positive half of each cycle, while the relay NX will respond only to the negative half of each cycle upon closure of the contact C1.

The phase-shifting circuit is capable of shifting the voltage applied to the transformer T2 (for operating the relays PX and NX) linearly from approximately zero to approximately 180° during each half cycle of the potential E4. The phase of the voltage E2 is shifted from that of E4 by applying a saw-tooth wave form of current to the control winding W3 of the saturable reactor A. The current flowing through the winding W3 of the saturable reactor A is large at the beginning of each half cycle of the source potential E4 causing the potentials E4 and E2 to be nearly in phase. As time increases the current through winding W3 decreases and voltage E2 will be made to lag voltage E4. The angle of lag will increase linearly with time up to approximately 180° for each half cycle of the E1 or E4 voltage. At the end of the 180° phase shift, the current in winding W3 is returned to its original value that it had at the beginning of the half cycle and the operation repeated during the following half cycle. The magnetic biasing current for the W3 winding of the saturable reactor A is obtained through a saw-tooth generator and phase inverter circuit.

The saw-tooth generator for developing a saw-tooth wave form of current comprises a gas discharge tube V2, a capacitor 30 connected across a source of direct current having terminals B—N through a resistor R1 and a contact C2. The contact C2 is connected to operate in synchronism with the contact C1. Connected in parallel with the capacitor 30 in series with a cathode resistor R7 is the anode cathode circuit of the gas discharge tube V2. The capacitor 30 is charged during each cycle of the saw-tooth current wave form by the charging current from the direct current source B—N through contact C2 and resistor R1 until the ionization potential of the gas discharge tube V2 is reached. At this time tube V2 becomes conducting and discharges the capacitor 30 to the gas tube V2.

deionization voltage, causing the tube **V2** to cease conduction. The cycle is then repeated.

Connected between the capacitor **30** and the resistor **R1** is the control grid of an amplifying tube **V3** which is provided with an anode and a cathode as well as the control grid. The anode is connected to the direct current source terminal **B** through a resistor **R5**, and the cathode is connected to the terminal **N** of the direct current source **B**—**N** through the resistor **R3**.

Connected to a point between the anode of the tube **V3** and the resistor **R5** is the control grid of a phase inverter tube **V4**. The anode of this inverter tube is connected to the **B** terminal of the direct current source **B**—**N** through the control winding **W3** of the saturable reactor **A**. The cathode is connected to the **N** terminal of the direct current source through a resistor **R4**.

To obtain the proper effective bias on the tubes **V3** and **V4** to a point of low distortion, the cathode of tube **V3** is connected to the **B** terminal of the direct current source through the resistors **R2** and **R12**. The cathode of tube **V4** is connected to the terminal **B** of the direct current source through resistor **R2**.

To assure proper sequential operation of the phase-shifting circuit, the control grid of the gas tube **V2** is connected through a 90° phase-shifting resistor condenser network comprising the resistors **R9**, **R10**, condensers **28** and **22**, and the resistor **R11**. The resistor condenser network, in turn, is connected to the secondary **S2** of transformer **T1** through a full-wave rectifier tube **V1**. The parts are so arranged that when the reference potential **E1** is going through zero the grid of the tube **V2** is at its maximum potential causing tube **V2** to conduct.

The tube **V1** has its two anodes connected to the opposite ends of the secondary winding **S2**, and its cathodes connected through the 90° phase-shifting network to a center tap **33** of the secondary winding **S2**.

The resistor **R9** has one end connected to the cathodes of the tube **V1**, and the other end connected to one end of the resistor **R10** and one end of capacitor **28**. The other end of the resistor **R10** is connected to one end of the capacitor **22**, one end of the resistor **R11**, and the grid of the tube **V2**. The other end of the resistor **R11** is connected to the remaining ends of the capacitors **22** and **28** and to the center tap **33** of the secondary winding **S2**.

Connected between the resistors **R11** and ground is a bias battery **23** for biasing the grid of the tube **V2** to the proper bias level.

Connected to a point between the cathode of the tube **V2** and the resistor **R7** is the grid of the reset tube **V5**. This tube **V5** has an anode circuit that can be traced from the **B** terminal of the direct current source **B**—**N** through conductor **27**, the lower winding **19** of relay **PX**, through conductor **24**, the lower winding **21** of the relay **NX**, the anode of the cathode of tube **V5**, through the bias battery **29** and ground to terminal **N** of the source. The rectifiers **25** and **26** in this anode circuit are used to improve the operation of the fast acting relays **PX** and **NX**.

The battery **29** is provided between cathode of tube **V5** and ground to bias the tube to normal cut-off.

I will now follow a typical operation of my cycle counting means. With the contact **C1** open and the contact **C2** closed, the alternating current reference potential **E1** is applied by the transformer **T1** to the transformer **T2** through the phase-shifting circuit comprising the secondary **S1** of transformer **T1**, resistor **R6** and saturable reactor **A**. This shifts the phase of the voltage **A2** with respect to that of the voltage **E4**.

The phase of voltage **E2** is shifted with respect to the voltage **E4** by applying a saw-tooth wave form of current, developed by resistor **R1**, capacitor **30** and tube **V2**, and amplified by tubes **V3** and **V4**, to the control winding **W3** of the saturable reactor. The current flowing through the winding **W3** is large at the beginning of each half

cycle of voltage **E4**, causing the saturable reactor **A** to be saturated and the voltages **E4** and **E2** to be nearly in phase. As time increases the current through the winding **W3** decreases lowering the magnetic bias in saturable reactor **A** and causing the voltage **E2** to lag voltage **E4**. The angle of lag will increase with time up to approximately 180° for each half cycle of voltage **E1** whereupon the current in winding **W3** will be returned to the value that it had at the beginning of the cycle. 10 This operation will be repeated during one or more following half cycles.

Through this arrangement the voltage **E2** is made to remain at zero through each half cycle of the voltage **E4** as long as the contact **C2** is closed.

15 At the end of each half cycle of the reference potential **E1** tube **V2** becomes conducting and the current flowing through resistor **R7** develops a voltage which is applied to the grid of the tube **V5**. This grid applied voltage causes the tube **V5** to conduct in such a manner as to pass current in the proper direction through the windings **21** and **19** of the relays **NX** and **PX** to move the contacts of these relays to the positions shown in the drawing. It follows therefore that if these contacts do not already occupy the positions shown in the drawing they 20 will move to these positions.

When the contact **C1** is closed and the contact **C2** is opened, which may occur at any time during the cycle of voltage **E1**, the flow of charging current for the capacitor **30** is stopped and the capacitor remains at the 25 potential to which it was charged at the time when contact **C2** becomes opened. The holding of this capacitor to its charged level causes the tubes **V3** and **V4** to continue to conduct at the level established at the time the contact **C1** became closed and the contact **C2** became opened. The resulting current in winding **W3** of reactor **A** causes the magnetic bias of the reactor to remain at the level obtained at the time the contact **C1** was closed and the contact **C2** opened. Since the magnetic bias in the core of the saturable reactor is maintained constant, the voltage **E2** will then start at zero and rise in step with the reference potential. This potential is fed through the transformer **T2** to the relays **PX** and **NX**, respectively. This causes the relay **PX** to be energized with the positive half cycles of the voltage **E2**, and the 30 relay **NX** to be energized with the negative half cycle of the voltage **E2** until the contact **C1** is again opened and the contact **C2** is again closed.

With the contact **C2** again in its closed position, the saw-tooth generator will again become operative and the 35 tube **V2** will be made to conduct current at the end of the half cycle of the voltage **E4** flowing at the instant the contact **C1** becomes closed as heretofore explained. The current passing through tube **V2** also flows through its cathode resistor **R7** and develops a potential across 40 the resistor which exists in series with the grid to cathode circuit of tube **V5**, and drives tube **V5** into a state of conduction. This will therefore cause the relays **PX** and **NX** to occupy their initial (or normal) positions as shown in the drawings.

60 I will now describe the complete cycle of operation of the counting relays **PX** and **NX** for one full cycle of operation thereof, and in response to the several half cycles from the secondary **S3** of transformer **T2**. The relay **PX** is energized by successive positive half cycles and the relay **NX** is energized in response to the interlinking successive negative half cycles.

For illustrative purposes suppose that a time interval to be measured has just begun and the contact **C1** is closed and **C2** is opened. Furthermore, assume that the 65 potential at the top terminal of the winding **S3** is just starting to go positive with respect to the bottom terminal. The lower terminal consequently is starting negative with respect to the top terminal. Current will flow from the top terminal of winding **S3**, through contact **C1**, rectifier 70 **17**, closed contact **14** of relay **NX**, winding **18** of re-

lay **PX** and back to the bottom terminal of the winding **S3**. This energizes relay **PX** which in turn closes its contact **13** and opens its contact **12**. Relay **NX** will not be energized during this half cycle due to the direction in which rectifier **16** is poled. However, during the succeeding half cycle the potential of the top terminal of the winding **S3** will be negative with respect to the bottom terminal. This allows the current to flow from the bottom terminal of winding **S3** through conductor **24**, the top winding **20** of relay **NX**, the closed contact **13** of relay **PX**, rectifier **16**, and back to the top terminal of winding **S3** through the contact **C1**. This energizes relay **NX** which closes its contact **15** and opens its contact **14**. During this half cycle relay **PX** is not energized due to the direction in which rectifier **17** is poled.

The potential from the winding **S3** has now completed a full cycle of operation while the relays are only at the midway point of a complete cycle of operation.

The next succeeding half cycle will again make the potential of the top terminal of the winding **S3** positive with respect to the bottom terminal. Current will now flow from the top terminal of **S3** through the contact **C1**, rectifier **17**, contact **15** of relay **NX**, the lower winding **19** of relay **PX**, and back to the negative terminal of winding **S3**. The relay **PX** once again will be energized which returns its contacts to the original position, that is, contact **12** will be closed and contact **13** will be opened. Again relay **NX** is not energized during this half cycle because of the direction in which rectifier **16** is poled. During the following half cycle the potential of the top terminal of winding **S3** will again be negative and the bottom terminal positive. Current will now flow from the bottom terminal of **S3**, through conductor **24**, winding **21** of relay **NX**, closed contact **12** of the relay **PX**, rectifier **16**, contact **C1**, and back to the top terminal of winding **S3**. This energizes relay **NX** which returns contact **14** to the closed position and contact **15** to the open position as shown in the drawings. Again during this half cycle relay **PX** is prevented from operating due to the way in which rectifier **17** is poled.

The relays **PX** and **NX** have thus completed one full cycle of operation while the potential from the winding **S3** has completed two complete cycles. This cyclic variation continues as long as contact **C1** remains closed and **C2** opened. The relays **PX** and **NX**, thus, are alternately energized once during each half cycle of the potential **E2** as long as contact **C1** is closed and the contact **C2** is opened.

It is therefore obvious that the relays **PX** and **NX** will start operating immediately upon the closure of the contact **C1** and the opening of the contact **C2** to count the succeeding cycles of the reference potential until such time as contact **C1** is again opened and the contact **C2** is closed. This ability of the relays **PX** and **NX** to follow the reference potential from the time the contacts **C1** and **C2** are initially operated until they are restored to the position shown is used to measure the elapsed time interval.

The component values of the phase shifting network are not critical, and satisfactory results may be obtained with a transformer **T1** which develops a voltage **E4** of 100 volts in the secondary winding **S1**. Also, the values of resistor **R6** and saturable reactor **A** are not critical, however, a definite relationship must be maintained between their values. Resistor **R6** must be small in comparison to the maximum impedance of windings **W1** and **W2** of the saturable reactor **A**, and large in comparison to the minimum impedance of these windings. A suitable value for resistor **R6** is 400 ohms when used in conjunction with a saturable reactor having controlled windings **W1** and **W2** whose impedance can be varied from approximately 50 or 75 ohms to approximately 2,000 or 2,500 ohms. Hence, it is desirable that the saturable reactor have a large impedance ratio, that is the ratio of the maximum to the minimum impedance in order that

the phase shift angle may be varied through a large range of values.

The magnitude of the energizing current for the control winding **W3**, as needed to produce the phase shifting action, is dependent upon the number of turns contained within the control winding. The maximum current flowing in the winding and the number of turns on the winding should be capable of developing a magnetomotive force of sufficient magnitude to saturate the core of the saturable reactor. With a saturable reactor of reasonable design, a maximum current of 100 milliamperes will develop sufficient saturating flux. As it is desirable that the saturable reactor have a large impedance ratio, the minimum control winding current should be zero. Therefore, the control winding current for the saturable reactor possesses a saw-tooth wave form having a maximum value of 100 milliamperes at the beginning of each half cycle of the voltage **E4** and gradually decreases to zero at the end of the half cycle.

Although I have herein shown and described only one form of phase-shifting means embodying my invention it is to be understood that various changes and modifications may be made therein within the scope of the appended claims without departing from the spirit and scope of my invention.

Having thus described my invention, what I claim is:

1. Timing means, comprising a source of alternating potential, at least one cycle counting relay, a first transformer having a primary winding connected to said source and at least one secondary winding, a phase shifting means connected to said secondary winding, a second transformer having a primary and a secondary winding, said primary winding of said second transformer being connected to said secondary winding of said first transformer and said phase-shifting means, said secondary winding of said second transformer being connected to at least one cycle counting relay through a normally open contact, said phase-shifting means being arranged to cause said second transformer primary winding potential to remain at substantially zero through each half cycle of said alternating source potential prior to the closing of said normally open contact, and said second transformer potential being capable of following said alternating source potential after closure of said normally open contact.

2. Timing means, comprising a source of alternating potential, a plurality of counting relays, a first transformer having a primary winding connected to said source and at least one secondary winding, a phase-shifting means connected to said secondary winding, a second transformer having a primary and a secondary winding, said primary winding of said second transformer being connected to said secondary winding of said first transformer and said phase-shifting means, said secondary winding of said second transformer being connected to said cycle counting relays through a normally open contact, said phase-shifting means being arranged to cause said second transformer primary potential to remain at substantially zero through each half cycle of said alternating source potential prior to the closing of said normally open contact, said second transformer potential being capable of following said alternating source potential after closure of said normally open contact, said phase-shifting means including a saturable reactor and a saw-tooth wave form generator, and said saw-tooth generator being provided with synchronizing means for synchronizing said saw-tooth generator with said source potential such that said saturable reactor causes said second transformer primary potential to lag said source potential with respect to time.

3. Timing means, comprising a source of alternating potential, a first transformer having a primary winding connected to said source and at least one secondary winding, a phase shifting means connected to said secondary winding, a second transformer having a primary and a secondary winding, said primary winding of said second transformer being connected to said secondary winding of

said first transformer and said phase-shifting means, said secondary winding of said second transformer being connected to cycle counting relays through a normally open contact, said phase-shifting means being arranged to cause said second transformer primary potential to remain at substantially zero through each cycle of said alternating source potential prior to the closing of said normally open contact, said second transformer potential being capable of following said alternating source potential after closure of said normally open contact, said phase-shifting means including a saturable reactor and a saw-tooth wave form generator, said saw-tooth generator being provided with synchronizing means for synchronizing said saw-tooth generator with said source potential such that said saturable reactor will cause said second transformer primary potential to lag said source potential with respect to time keeping said second transformer potential at zero as long as said normally open contact remains open, said saw-tooth generator comprising an alternately charged and discharged capacitor for controlling the grid of a vacuum tube amplifier, said vacuum tube amplifier being used to control the grid of a phase inverter tube, and the anode of said phase inverter tube is connected to a winding of said saturable reactor.

4. Timing means, comprising a source of alternating potential, a first transformer having a primary winding connected to said source and at least one secondary winding, a phase shifting means connected to said secondary winding, a second transformer having a primary and a secondary winding, said primary winding of said second transformer being connected to said secondary winding of said first transformer and said phase-shifting means, said secondary winding of said second transformer being connected to cycle counting relays through a normally open contact, said phase-shifting means being arranged to cause said second transformer primary potential to remain at substantially zero through each half cycle of said alternating source potential prior to the closing of said normally open contact, said second transformer potential being capable of following said alternating source potential after closure of said normally open contact, said phase-shifting means including a saturable reactor and a saw-tooth wave form generator, said saw-tooth generator being provided with synchronizing means for synchronizing said saw-tooth generator with said source potential such that said saturable reactor will cause said second transformer primary potential to lag said source potential with respect to time keeping said second transformer potential at zero as long as said normally open contact remains open, said saw-tooth generator comprising an alternately charged and discharged capacitor for controlling the grid of a vacuum tube amplifier, said vacuum tube amplifier being used to control the grid of a phase inverter tube, said phase inverter tube being connected to a winding of said saturable reactor, said synchronizing including a gas discharge tube being connected in parallel with said capacitor for discharging said capacitor, and said discharge tube having a control grid connected to respond to said source potential to cause said discharge tube to conduct when said source potential passes through zero.

5. Timing means, comprising a source of alternating potential, a first transformer having a primary winding connected to said source and at least one secondary winding, a phase shifting means connected to said secondary winding, a second transformer having primary and secondary windings, said primary winding of said second transformer being connected to a secondary winding of said first transformer and said phase-shifting means, said secondary winding of said second transformer being connected to a plurality of cycle counting relays through a normally open contact, said phase-shifting means being arranged to cause said second transformer primary potential to remain at substantially zero through each half cycle of said alternating source potential prior to the

closing of said normally open contact, said second transformer potential being capable of following said alternating source potential after closure of said normally open contact, said phase-shifting means including a saturable reactor and a saw-tooth wave form generator, said saw-tooth generator being provided with synchronizing means for synchronizing said saw-tooth generator with said source potential such that said saturable reactor will cause said second transformer primary potential to lag said source potential with respect to time keeping said second transformer primary potential at zero as long as said normally open contact remains open, said saw-tooth generator comprising an alternately charged and discharged capacitor for controlling the grid of a vacuum tube amplifier, said vacuum tube amplifier being used to control the grid of a phase inverter tube, and said phase inverter tube being connected to a winding of said saturable reactor, said synchronizing means comprising a gas discharge tube being connected in parallel with said capacitor for discharging said capacitor, said discharge tube having a control grid connected to respond to said source potential to cause said discharge tube to conduct when said source potential passes through zero, and biasing means responsive to said discharge tube operation for biasing said cycle counting relays to their initial position.

6. Timing means, comprising a source of alternating potential, a first transformer having a primary winding connected to said source and at least one secondary winding, a phase shifting means connected to said secondary winding, a second transformer having primary and secondary windings, said primary winding of said second transformer being connected to a secondary winding of said first transformer and said phase-shifting means, said secondary winding of said second transformer being connected to cycle counting relays through a normally open contact, said phase-shifting means being arranged to cause said second transformer primary potential to remain at substantially zero through each half cycle of said alternating source potential prior to the closing of said normally open contact, said second transformer potential being capable of following said alternating source potential after closure of said normally open contact, said phase-shifting means including a saturable reactor and a saw-tooth wave form generator, said saw-tooth generator being provided with synchronizing means for synchronizing said saw-tooth generator with said source potential such that said saturable reactor will cause said second transformer primary potential to lag said source potential with respect to time keeping said second transformer potential at zero as long as said normally open contact remains open, said saw-tooth generator comprising an alternately charged and discharged capacitor for controlling the grid of a vacuum tube amplifier, said vacuum tube amplifier being used to control the grid of a phase inverter tube, said phase inverter tube being connected to a winding of said saturable reactor, said synchronizing means including a gas discharge tube being connected in parallel with said capacitor for discharging said capacitor, said discharge tube having a control grid connected to respond to said source potential to cause said discharge tube to conduct when said source potential passes through zero, and biasing means responsive to said discharge tube operation for biasing said cycle counting relays to their initial position during first cycle of source potential following a prior operation, said biasing means comprising a vacuum tube having an anode, a cathode and a control grid, said anode being connected to the positive terminal of a source of direct current through said counting relays, said cathode being connected to the negative terminal of said source of direct current, and said grid being connected to said discharge tube for causing said vacuum tube to conduct.

7. A control circuit for a pair of cycle counting relays comprising a source of alternating potential, a first transformer having a primary winding connected to said source

and at least one secondary winding, a second transformer having primary and secondary windings, a phase shifting means connected to said secondary winding, said primary winding of said second transformer being connected to said secondary winding of said first transformer and said phase-shifting means, said secondary winding of said second transformer being connected to a pair of cycle counting relays through a normally open contact in a manner such that one relay is energized in response to the positive half of an alternating cycle while the other relay is energized in response to the negative half of the alternating cycle of said source potential, said phase-shifting means being arranged to cause said second transformer primary potential to remain at substantially zero through each half cycle of said alternating source potential prior to the closing of said normally open contact, said second transformer potential being capable of following said alternating source potential after closure of said normally open contact.

8. A control circuit for cycle counting relays comprising, a source of alternating potential, a plurality of cycle counting relays, said counting relays being connected to said alternating source through a circuit including a phase-shifting means and a normally open contact, the potential of said circuit for said counting relays being maintained at substantially zero by said phase-shifting means during each half cycle of said source potential, and means for causing said phase-shifting means to cease phase shifting of said circuit potential for said relays allowing said relays to be immediately capable of following said source potential at the time of closure of said normally open contact.

9. A control circuit for cycle counting relays comprising, a source of alternating potential, a plurality of cycle counting relays, said relays being connected to said alternating source through a phase-shifting means and a circuit closing means, said phase-shifting means being capable of providing a counting relay potential capable of being shifted with reference to said source potential for maintaining said counting relay potential at substantially zero during each half cycle of said source potential, said phase-shifting means ceasing to phase shift said counting relay potential allowing said relays to be immediately capable of following said counting relay potential at the time of closure of said circuit closing means, said phase-shifting means including a saturable reactor for continually phase shifting said counting relay potential for said relays throughout the period of time prior to closure of said circuit closing means.

10. A timing control circuit comprising a source of alternating potential, a plurality of cycle counting relays, said counting relays having a circuit connecting means for at times connecting said counting relays to said alternating source through a phase-shifting means, said phase-shifting means being capable of shifting the phase of its output potential with reference to said source potential keeping said output potential at substantially zero prior to connecting said counting relays to said source by said circuit connecting means, said phase shifting means being arranged to cease its phase shifting at the time of operation of said circuit connecting means allowing said counting relays to follow said source potential.
